PROCESS OF AND APPARATUS FOR DETERMINING BENZOL IN GAS.

1,163,654.

Specification of Letters Patent.

Patented Dec. 14, 1915.

Application filed February 2, 1915. Serial No. 5,639.

To all whom it may concern:

Be it known that I, CARL L. O. GRAUL, a citizen of the United States, residing at Chicago, in the county of Cook and State of Illinois, have invented a new and Improved Process of and Apparatus for Determining Benzol in Gas, of which the following is a specification.

In the treatment of the gas resulting from the destructive distillation of coal, as in coke ovens, the gas is fractionated to separate out and recover its components of value. Among these is benzol which is separated from the gas by, primarily, causing it to be absorbed by a suitable absorbing agent. Where it is desirable to recover and market the benzol as such the commercial success of the operation depends on the completeness of its recovery, any benzol which passes the absorber being eventually burned with the gas and being thus lost as a marketable product.

The object of my improvements is to provide means for testing the treated gas to determine the presence or absence of benzol therein and thus enable precautions to be taken looking to its more complete separation and recovery.

My invention is based upon the fact that the illuminating power of a gas carrying benzol is greater than that of a gas of otherwise precisely the same composition but in which no benzol vapor is present. Thus by drawing off from a stream or body of gas a portion thereof, dividing this portion into two parts, treating one of these parts to positively remove any benzol present therefrom and finally separately burning the two parts and comparing the illuminating power of the two gas flames I am able to determine the presence or absence of benzol in the original mass or stream of gas and the proportion in which it is present.

The invention will be best understood by describing it in connection with the accompanying drawing, forming a part hereof, which is a diagrammatic representation of a form of apparatus which may be advantageously employed in carrying it into effect reference being made thereto by means of the numbers indicating the several parts.

The gas to be tested is drawn off from a body thereof, as a stream of gas flowing through pipe, 1, which may be the outlet pipe from the usual benzol absorber (not

shown in the drawing), through pipe, 2, whence it passes by pipe, 3, through a bath of picric acid, indicated at, 4, whereby any naphthalene present in the gas, which, if remaining in the gas, would have an illuminating effect similar to benzol, is removed. From the picric acid bath the gas passes by pipe, 5, and is then divided into two parts one of which passes by pipe, 6, directly to an Argand gas burner, 7. The pipe, 6, is connected with a pressure regulator, 8, which, as shown, may be a counterweighted gas holder of small size, the movements of which control a regulating cock, 9, in the pipe, 6, whereby the pressure of the gas going to the burner, 7, may be determined and regulated. The other part of the gas is treated, in any usual or suitable manner to remove any contained benzol, as by being passed by pipe, 10, through a bath, 11, of an oil capable of absorbing benzol. It is then passed by pipe, 12, through a mass of nut coke to remove any oil that may have been mechanically carried over from the bath, 11, and thence by pipes, 13, and 14, to an Argand burner, 15, similar to burner, 7. The pressure of the gas passing through pipe, 14, is regulated by a pressure regulator, 16, and cock, 17, in the same manner as the gas passing through pipe, 6, to burner, 7. The pipes, 6, and, 14, are both connected, at points beyond the pressure regulators, with U gages, 18, 19, whereby the pressure of the gas passing through the pipes may be observed to the end of adjusting the regulation of same.

In carrying the process into effect the two gas burners are first standardized against each other by delivering to both gas of the same quality. This is accomplished by closing the cocks, 22 and 23, and opening the cock, 24, so that the gas delivered to both burners passes through the picric acid bath, 4, and the test benzol-absorber, 11, before going to the burners. The sight box, 25, which carries a Bunsen or Leeson star disk, such as is used in the determination of the absolute candle power of a gas, is set at zero on the gage, 26, and the pressures of the gas flowing to the burners is adjusted until the disk in the sight box is equally illuminated on both sides, the respective pressures necessary to accomplish this being noted. The cocks are then set so that the gas delivered to burner, 7, does not pass through the test benzol absorber, 11, while the gas going to

burner, 15, does pass through it, and, if necessary, the gas pressures are readjusted to the same point as before. If benzol is present in the gas tested, burner, 7, will receive 5 gas carrying this benzol while the gas to burner, 15, will be deprived of its benzol by passing through the absorber, 11. Under these conditions burner, 7, will give more 10 light than burner, 15, and the point of equal illumination, as indicated on the disk in the sight box, 25, will be shifted away from the zero point on the gage, the extent of such shifting, determined by first burning gas containing a known proportion of benzol, 15 indicating the proportion of benzol contained in the gas. If, on the other hand, no benzol is present in the gas tested, the gas 20 will suffer no change in passing through the absorber, 11, the two burners will give an equal amount of light, and the point of equal illumination will remain at zero on the gage as it was during the standardization. In this manner I am able to readily 25 determine the presence of benzol in a body of gas or to obtain a continuous indication of its presence in a flowing stream of gas, thus enabling seasonable precautions to be adopted to effect a more complete removal of the benzol from the gas, the advantage 30 of which will be readily understood by those skilled in the art.

What I claim as new and desire to secure by Letters Patent is:

1. The hereinbefore described process of 35 determining the presence of benzol in gas which consists in treating a portion of the gas to remove any benzol present therein, burning the gas so treated and the untreated gas at separate burners and comparing the 40 illuminating power of the gas flames.

2. The hereinbefore described process of determining the presence of benzol in gas which consists in treating the gas to be tested with picric acid to remove the naph-

thalene therefrom, treating a portion of the 45 gas to remove the benzol therefrom, burning the gas from which the benzol has been removed and the gas with its benzol content at separate burners, and comparing the illuminating power of the gas flames. 50

3. The process of determining the presence of benzol in gas which consists in drawing off from the gas a portion thereof, dividing such portion into two parts, treating one of said parts to remove any benzol present therein, burning the part so treated and the untreated part at separate burners under conditions giving gas flames of equal illuminating power with gas of one quality, and comparing the illuminating power of the 60 gas flames. 55

4. The process of determining the presence of benzol in gas which consists in continuously drawing off from a stream of gas a portion thereof, dividing such portion into 65 two parts, treating one of said parts to remove any benzol present therein, burning the part so treated and the untreated part at separate burners under conditions giving gas flames of equal illuminating power with 70 gas of one quality and comparing the illuminating power of the gas flames.

5. A device for determining the presence of benzol in gas comprising a gas way, two 75 gas burners, a connection from said gas way to each of said burners, means for regulating the gas pressure at said burners, means for separating the benzol from the gas flowing to one of said burners and means for comparing the illuminating power of the gas 80 flames at said burners.

In testimony whereof, I have hereunto subscribed my name, this 22nd day of January A. D., 1915.
